FUSE TESTING DEVICE

Morris Podell, Far Rockaway, N. Y.

Application February 6, 1932, Serial No. 591,363

13 Claims. (Cl. 175—183)

My invention relates to a new and improved fuse testing device.

One of the objects of my invention is to produce an improved fuse testing device comprising a plurality of rigid members having conducting means which are in circuit with a suitable detector, such as a glow lamp, or the like.

Another object of my invention is to provide a device which shall be simple and cheap to manufacture and which shall be of durable construction.

Another object of my invention is to provide a device of this type comprising pivoted rigid members.

Another object of my invention is to provide a device of this type which can also serve as a fuse puller.

Other objects of my invention will be set forth in the following description and drawings which illustrate a preferred embodiment thereof, it being understood that the above general statement of the objects of my invention is intended to merely generally explain the same and not to limit it in any manner.

Fig. 1 is a side elevation.

Fig. 2 is a front elevation.

Fig. 2a is a partial side elevation showing the side opposite to that which is illustrated in Fig. 1.

Fig. 3 is a sectional view on the line 3—3 of Fig. 2.

Fig. 4 is an inner elevation of one of the legs.

Fig. 5 is a side view of Fig. 4.

Fig. 6 is an inner elevation of the other leg.

Fig. 7 is a side elevation of Fig. 6, the insert being omitted.

Fig. 8 is a diagrammatic view of the circuit.

Fig. 9 is an elevation showing the insert which is located in one of the legs.

Fig. 10 is a side elevation of Fig. 9.

Fig. 11 is a sectional view on the line 11—11 of Fig. 2.

Fig. 12 is a sectional view on the line 12—12 of Fig. 2.

Fig. 13 is a vertical sectional view of one of the end caps.

The device comprises a pair of legs 1 and 2, preferably made of pieces of insulating material and said legs are connected to each other by a pivot member 9 which can be made of metal or any other suitable material and which is of rivet-like construction. The outer ends of said rigid legs may be shaped so that the device can be used for handling a fuse F.

As shown in Fig. 1, the inner end of the leg 1 comprises two leg members 1a and 1b which are

made of fibre or other suitable insulating material.

As shown in Fig. 2a, the outer end of the leg 1 comprises additional members or layers 1c and 1d. These layers or members are connected to each other and to members 1a and 1b by means of rivets 3.

As shown in Fig. 2a, the inner end of the leg 2 comprises outside members or layers 2a and 2b, and an intermediate insert 2c. As shown in Fig. 1, the outer end of the leg 2 comprises the layers 2a and 2b and intermediate layers 2c and 2d. The insert 2c is made of moldable insulating material and openings are provided therein during the molding operation in order to leave space to accommodate the resistance R and the detecting or indicating device 6. In this case, the detecting or indicating device 6 is a glow lamp or neon lamp, but it may be any type of lamp, and any type of indicating device may be used. In order to securely hold the glow lamp in position, and to allow for variations in the sizes of glow lamps, a resilient member 5a made of rubber or other suitable material is suitably connected to the insert 2c. The indicating device may be connected to the circuit in any suitable manner.

As shown in Fig. 12, this resilient member 5a partially encloses and abuts the lamp 6. As shown in Figs. 6 and 12, the member 2a is provided with an opening 12 which is closed by a sheet of mica or other light permeable material 12a so that the glow of the lamp can be readily detected.

The resistance R is conventionally indicated in Fig. 9. This resistance is preferably a carbon resistance of high value, so that very small current is sent through the lamp 6, when the device is used for testing a fuse. The lamp can be connected to the terminals to be tested either in series or in shunt. A series connection is shown in the drawings, and the use of the high carbon resistance makes it possible to use the same bulb on circuits having different commercial voltages, such as 110 volts, 220 volts and as high as 600 volts.

Conductors 7a and 7b are connected in any suitable manner to the terminals of the glow lamp and for this purpose the device may be provided with a socket of any conventional type into which the glow lamp may be placed. The resistance R is connected to a conducting wire 7b whose inner end is curved to hook-like shape, so that this hook-like end abuts the inner end of the leg 2. The conductor 8 has a correspondingly shaped hook-like end which abuts the inner

end of the leg 1. Metal thimbles 4 and 5 can be connected to the inner ends of the legs 1 and 2. This could be accomplished by means of a drive fit, but I prefer to have some of the rivets 5 extend through the metal thimbles 4 and 5. The metal thimbles 4 and 5 are thus pressed firmly against the hook-like inner ends of the conductors, in order to insure firm contact. The outer end of the conducting wire 7a is bent to 10 form a loop member L' and the outer end of the conducting wire 8 is bent to form a loop L. These wires may be uninsulated as they are securely held in suitable recesses G provided therefor in the insulating material from which the 15 legs of the device are made. For example, and as shown in Fig. 3, the members 1a and 1b may be provided with recesses in which the wire 8 is located. The loops L and L' are free from insulation so that they can contact with each 20 other. The wires 7a and 7b are located in a recess provided in the insert 2c. The loops L and L' pass around the pivot member 9 without touching the same.

Figs. 4 and 6 show how each of the legs is provided with an arcuate groove G in order to 25 respectively receive the loops L and L'. Said loops L and L' can slide one upon the other with little or no friction, while being maintained in firm rubbing contact so as to complete the circuit between them.

As shown in Figs. 4, 5 and 8, the wire 8 passes out of the leg member 1a, through an opening 10. Said loops L and L' are concentric with the axis about which the rigid legs turn.

Although I have shown a combination device 35 for testing the fuse and for pulling the fuse from its socket, the invention is not necessarily limited to such combination device. Heretofore it has been customary to use a glow lamp to which 40 flexible conductors were connected in order to test a fuse, and the use of rigid members to one of which the detector device is connected, presents numerous advantages.

The inner ends of the conducting wires may be 45 considered as constituting outer conducting terminals, which are enlarged by the metal members 4 and 5. It is not necessary to make the device throughout of insulating material although this is preferred, because any part of 50 the device could be made from conducting material, such as metal, by suitably insulating the corresponding portion or portions of the conducting wires. Although I have shown the indicating device as being mounted within one 55 of the legs, it would not be departing from my invention if said indicating device were mounted in any manner upon any of the rigid members. Said indicating device could be a buzzer or other acoustic device although the use of a glow lamp 60 is preferred, since it requires a very minute current to cause the same to glow.

Of course it would not be departing from the invention if a plurality of detector devices were utilized, and said detector devices could be mounted 65 on one or on both of the rigid legs.

While I have stated that the device can be used for testing a fuse, said device could obviously be used for testing any circuit by connecting the wires 8 and 7b to the terminals of the circuit to 70 be tested.

For example, the metal members 4 and 5 could have serrated outer surfaces in order to prevent them from slipping along the ends of the fuses or buss-bars, etc. Likewise the members 75 4 and 5 could be replaced by discs having ser-

rated outer surfaces and held between the respective leg members or layers by rivet-like pivot members, so that the outer surfaces of said discs project beyond the ends of the legs.

I claim:

1. A circuit testing device comprising a pair of rigid members pivotally connected to each other, a detector device mounted on one of said rigid members, and conducting means mounted on said rigid members and connected to said detector device and adapted to complete the circuit between said detector device and the terminals of the circuit to be tested, said rigid members being made throughout of insulating material. 10

2. A circuit testing device comprising a pair of rigid members pivotally connected to each other, a detector device mounted on one of said rigid members, conducting wires connected to said detector device and respectively mounted on said rigid members, the adjacent ends of said conducting wires comprising portions which are in rubbing contact with each other, said conducting wires being adapted to complete the circuit between said detector device and the terminals of the circuit to be tested. 15

3. A circuit testing device comprising a pair of rigid members, a pivot member pivotally connecting said rigid members, a detector device mounted on one of said rigid members, wires mounted on said rigid members, one of said wires 20 having the detector device in its circuit, the adjacent ends of said wires being free from insulation and being in rubbing contact, that portion of each rigid member which is adjacent the uninsulated ends of the wires being made from insulating material, said wires extending to the exterior surfaces of said rigid members. 25

4. A circuit testing device comprising a pair of rigid members, a pivot member pivotally connecting said rigid members, a detector device 30 mounted on one of said rigid members, wires located within said rigid members, one of said wires having the detector device in its circuit, the adjacent ends of said wires forming loops 35 which are substantially concentric with the axis of said pivot member and which are in rubbing contact, said wires extending to the exterior surfaces of said rigid members, said rigid members being made of insulating material. 40

5. A combination fuse extractor and fuse testing device comprising a pair of rigid members, a pivot member pivotally connecting said rigid members, the outer ends of said rigid members being shaped to grip a fuse, a detector device mounted on the inner end of one of said rigid 55 members, wires mounted on said rigid members, one of said wires having the detector device in its circuit, the adjacent ends of said wires being free from insulation and being in rubbing contact, that portion of each rigid member which is adjacent the uninsulated ends of the wires being made 60 from insulating material, said wires extending to the exterior surfaces of said rigid members. 65

6. A combination fuse extractor and fuse testing device comprising a pair of rigid members, a pivot member pivotally connecting said rigid members, the outer ends of said rigid members being shaped to grip a fuse, a detector device mounted on the inner end of one of said rigid 70 members, wires mounted on said rigid members, one of said wires having the detector device in its circuit, the adjacent ends of said wires being free from insulation and being in rubbing contact, that portion of each rigid member which is adjacent the uninsulated ends of the wires being 75

made from insulating material, said wires extending to the exterior surfaces of said rigid members, the adjacent ends of said wires forming loops which are substantially concentric with the axis of said pivot member.

5 7. A combination fuse extractor and fuse testing device comprising a pair of rigid members made of insulating material, a pivot member pivotally connecting said rigid members, the outer ends of said rigid members being shaped to grip a fuse, a detector device associated with one of said rigid members, wires located within said rigid members, one of said wires having the detector device in its circuit, the adjacent ends of said wires being in rubbing contact, said wires extending to the exterior surfaces of said rigid members, and metal members located at the inner ends of said rigid members and respectively contacting with said wires.

10 8. A circuit-testing device comprising a pair of rigid members, a pivot connecting said rigid members, a detector device mounted on one of said rigid members, conducting wires connected to said detector device and respectively mounted within said rigid members so as to be turnable in unison therewith, the adjacent ends of said conducting wires comprising portions which are in rubbing contact with each other, said rigid members having recesses in which said adjacent ends are located, said adjacent ends being concentric with said pivot member, said conducting wires being adapted to complete the circuit between said detector device and the terminals of the circuit to be tested.

15 9. A combination fuse extractor and fuse-testing device comprising a first rigid leg and a second rigid leg, a pivot member connecting said rigid legs, each of said legs comprising an inner portion, each of said legs also comprising an outer portion, said outer portions being adapted to grip the fuse, the inner portion of the first leg comprising a plurality of rigid insulating members between which a wire is located, the outer portion of the first leg comprising said rigid insulating members, and also additional rigid insulating members between which the first mentioned rigid members are located, the inner portion of the second leg comprising spaced rigid members made of insulating material and having an intermediate insert in which there is located a detector device, and a second conducting wire which is connected to said detector device, the ends of said wires which are close to said pivot member being in rubbing contact with each other and being located in recesses which are provided in the respective legs, the inner portion of the first leg being located between the spaced rigid members of the second leg adjacent said pivot member.

20 10. A combination fuse extractor and fuse-testing device comprising a first rigid leg and a second rigid leg, a pivot member connecting said rigid legs, said legs being made of insulating material, each of said legs comprising an inner portion, each of said legs also comprising an outer portion, said outer portions being adapted to grip the fuse, the inner portion of the second leg having outer spaced rigid members, said spaced rigid members having an insert located between them, a detector device and a wire mounted in said insert, the first rigid leg being located between said spaced rigid members adjacent the pivot member, the first rigid leg also having a wire located therein, the ends of said wires which are close to said pivot member being in rubbing contact with each other and being located in recesses which are provided in the respective legs.

25 11. A circuit-testing device comprising a first rigid member and a second rigid member, said rigid members being made of insulating material, a pivot connecting said rigid members, said rigid members having recesses around said pivot, said recesses registering with each other, said rigid members having conducting members at their outer ends, the first rigid member having a detector device mounted thereon and connected to the respective outer metal member, said outer conducting members being connected with each other through said detector device by conducting means parts of which are located within said recesses.

30 12. A circuit-testing device comprising a first rigid member and a second rigid member, said members being connected by a pivot, said members being made of insulating material on both sides of said pivot, said rigid members having conducting members on their outer ends, the first rigid member having a detector device mounted thereon and connected to the respective outer conducting member, said outer conducting members being connected with each other and through said detector device by conducting means a part of which is exposed only at the adjacent surfaces of said rigid members adjacent said pivot pin, said conducting means being enclosed by said rigid members.

35 13. In an electric fuse tester, a pair of compassing legs of insulating material having pivoted connection with each other, a pair of test pins secured to the free end of said legs, a neon tube located in one leg and being visible through an aperture therein, a resistance unit, and conducting means in said legs for connecting said tube in circuit with said pins and said resistance unit.

MORRIS PODELL.
